UNITED STATES PATENT OFFICE

2,266,707

DOOR

Frank O. Goodman, Chicago, Ill.

Application April 3, 1939, Serial No. 265,631

11 Claims. (Cl. 20—20)

This invention relates to doors and particularly to doors for garages, barns and the like, which are employed to close large openings.

The principal object of the invention is to provide an improved door which can be readily fabricated and installed, easily operated, and employs a simple mechanism for removal from and return to the opening which requires no attention or adjustments.

Another object of the invention is to provide a door which can be lowered into its fully closed position and locked in that position and which will nevertheless permit the uppermost section of the door to be opened for ventilation.

Another object of the invention is to provide an improved bearing device which enables the door to be moved with greater facility and prevents any binding of the door regardless of how pressure is applied to the door when it is raised or lowered.

Another object of the invention is to provide an operating mechanism for the door which requires no overhead space and permits the door to be raised to a position immediately adjacent the ceiling of the room.

Other objects, advantages and capabilities of the invention are apparent from the following description thereof taken in conjunction with the accompanying drawing, in which a preferred embodiment of my invention is illustrated.

Figure 1 is a rear elevation of the door in closed position.

Fig. 2 is a fragmentary rear elevation illustrating a portion of the door with the uppermost section opened and the remainder of the door in closed position as shown in Fig. 1.

Fig. 3 is a view on the line 3—3 of Fig. 1 of a sectional elevation of a fragment of the uppermost sections 10 and 11 of the door with the related operating parts in closed position.

Fig. 4 is a sectional detail view of a fragment of the door taken on the line 4—4 of Fig. 2 showing the same portion of the door as is shown in Fig. 3, with the uppermost section of the door in open position.

Fig. 5 is a fragmentary detail in perspective of the bearing mounting of the uppermost section of the door showing the parts in their respective relation when the door is closed.

Fig. 6 is a fragmentary detail view in perspective of the same bearing mounting as shown in Fig. 5 with the parts in the relation occupied when the uppermost section of the door is open.

Fig. 7 is a perspective detail of the hardware

unit employed as the bearing mounting shown in Figs. 5 and 6.

Fig. 8 is a sectional detail view taken on the line 8—8 of Fig. 1 of the bearing unit one of which is mounted upon each end of each section of the door except the uppermost section.

Referring to the drawing, the door comprises a number of horizontal sections 10, 11, 12 and 13, which close the opening defined by the side posts 14, 14 and the lintel 15, which are provided with the stops 16 and 17.

The door sections are hinged together with hinges 18 at their horizontal edges. The hinges 18 are mounted so that the various sections may be swung inwardly.

Suitably mounted upon the side posts 14 and the ceiling of the room are the angle rails 19, 19 which rise vertically from the floor, are formed into curved portions 20 and terminate in the horizontal rails 21 which run along the ceiling of the room from which they are suspended.

Affixed to the lower edge of the lowest section of the door are anchors 22 by which cables 23 are secured to the door. These cables are run to the ceiling over appropriate pulleys and are attached to springs or counterweights to facilitate the raising of the door.

Each of the sections of the door except the uppermost section 10 is provided at its two upper corners with a bearing member shown in detail in Fig. 8. This bearing member is composed of the brackets 24 and 25, which form mountings by which the rivets 26, 27 and 28 are anchored. These rivets serve as axles upon which the rollers or wheels 29, 30 and 31 freely rotate. The peripheries of the wheels 29 and 31 ride upon the faces of one rail of the angle beam 19, while the periphery of the roller 30 rides upon an edge of the same rail. Each section of the door is thus held securely against displacement in any direction when the door is raised or lowered.

The uppermost section 10 of the door is provided at each end with a bearing unit of entirely different design. These bearing members form part of the operating mechanism by which the door is raised and lowered and by which the position of the uppermost section 10 of the door is controlled.

Two complete assemblies of the operating mechanism by which the uppermost section 10 of the door is swung into open position are employed, mounted respectively on the right hand and left hand sides of the door. In this description only the parts on the right hand side of the

door will be described. It is to be understood, however, that these parts are duplicated on the left hand side of the door, where they operate in exactly the same manner.

Attached to the door section 10 on each side, at a point slightly below its uppermost edge, are angle brackets 32 shown in detail in Fig. 7. The long leg of each angle bracket lies adjacent the inner face of the door and the short leg 33 lies adjacent the edge of the door section.

Pivoted to the short leg 33 upon the rivet 34 is the swinging bracket 35. The bracket 35, as shown in Fig. 7, is composed of a metal strip formed into a long arm 36, and then bent to form the arm 37 perpendicular thereto. The arm 37 is again bent at its outer end to form the flange 38 which is perpendicular to the arm 37 of the bracket 35, and parallel to the long arm 36 thereof.

While one end of the long arm 36 of the bracket 35 is pivoted to the angle bracket 32 at the pivot 34, the other end is provided with a rivet 39 which forms a pivot for the free link 40 and also serves as an axle for the wheel or roller 42. Affixed to the link 40 is the rivet 41 which serves as an axle for the wheel or roller 43, as shown in Fig. 5.

Pivoted to the flange 38 of the bracket 35 is the vertical rod 44 shown in Figs. 1 to 6, inclusive. This vertical rod 44 is guided by the ring bolt 45 through which it passes. The ring bolt 45 is secured to the uppermost section 10 of the door. The vertical rod 44 is broken and provided with a pivot 46 by which the lower portion 47 of the vertical rod is pivotally secured to the upper portion 44. This pivot is so placed as to be in alignment with the joint at which the door sections 10 and 11 meet, when the door is in position to be opened.

Below the rod 44, 47 is the toggle 48, 49. The upper end of the link 48 of the toggle is joined to the rod 47 by the pivot 53. The lower link 49 of this toggle is pivoted at 50 to the door section 11. The range of movement of the toggle is restricted and guided by the arm 51 which is pivoted to the door at 52 and to the pivot 53 which joins the rod 47 and the upper link 48 of the toggle. The lower link 49 of the toggle is pivotally secured to the operating bar 54 at the pivot 55. The operating bar 54 is also secured at its other end to the rotatable plate 56 and is slideable within the guide 57, which is secured to the door section 11.

The rotatable plate 56 is operated by the handle 58 and can be locked in the position in which it is shown in Fig. 1 by the conventional lock 59.

The operating bar 54 projects beyond the pivot 55 sufficiently far so that it may be projected through a slot in the remote rail of the vertical angle beam 19 and serve as a bolt to lock the door in closed position as is shown in Fig. 1.

The door may be provided with an auxiliary sliding bolt 60, mounted upon the rear face of the door, which can be slid through a slot in the remote rail of the vertical angle beam 19 to lock the door in closed position when the uppermost section 10 of the door is swung into open position. Similar provision may be made for locking the door in closed position by providing a hole 61 in the face of the vertical angle beam 19 through which a bolt may be projected to engage the bearing member assembly which is shown in detail in Fig. 8. Any other suitable means may be employed to bolt the door against

upward movement when the uppermost section 10 is held in open position.

The door may also be provided with a suitable handle 62 by which the door may be raised and lowered.

The operation of the door is as follows: When the door is in closed position as shown in Fig. 1 the bearing for the uppermost section 10 is in the position illustrated in Fig. 5. The long arm 36 of the bracket 35 projects horizontally from the vertical door section and the wheels 42 and 43 lie upon the flat rail of the curved portion 20 of the angle beam 19 upon which the bearings of the door ride. The front of the frame member 15 63 of the door section 10 is borne against the stop 17 below the lintel 15. The arm 36 of the bracket 35 is held in the horizontal position by the vertical rod 44 which is operated through the intervening links by the operating bar 54.

When the parts are in the respective positions illustrated in Fig. 5 the door cannot be raised, because the upper edge of the door section 10 bears against the sill 15 and the pivots 18 and 46 do not coincide and because the remote end 25 of the operating bar 54 projects through the vertical rail 19 and bolts the door in that position.

When it is desired to open the door, whether the uppermost section 10 is alone to be swung open to provide ventilation or the entire door is 30 to be lifted into its horizontal position beneath the ceiling of the room, the lever 58 on the rotatable plate 56 is swung toward the right. Because of their eccentric pivotal mounting upon the plate 56 the horizontal bars 54 are moved toward the middle of the door and their ends withdrawn from the slots in the vertical rail 19.

Simultaneously, the horizontal bars 54 swing the lower links 49 of the toggles about their pivots 50 and the toggles are opened as shown in 40 Fig. 2. The toggle is guided into an almost vertical position by means of the pivoted bar 51, which swings about its pivot 52, and restrains the toggle so that the links of the toggle assume practically a vertical position. The horizontal 45 motion of the bar 54 is thus translated into vertical motion of the rod 44, 47, which is pivoted to the flange 38, at the end of the long arm 36 of the bracket 35.

As the rod 44 moves upward it closes the angle 50 between the long arm 36 of the bracket 35 and the edge of the frame portion 63 of the uppermost section 10 of the door. As the bracket 35 is restrained by the engagement of the wheels 42 and 43 with the flat rail of the curved portion 55 20 of the angle beam 19, the closing of the angle between the bracket arm 36 and the frame portion 63 can be effected only by the swinging inwardly of the uppermost section 10 of the door about the hinges 18, by which sections 10 and 60 11 are connected. The uppermost section 10 of the door thus swings rearwardly into the room which is closed by the door, and the upper part of the door frame 63 comes to rest on the arm 37 of the bracket 35, which limits the extent of 65 movement of the frame 63 and serves as a carrier for the uppermost section 10 of the door. At the completion of this movement the parts shown in Fig. 5 assume the relationship shown in Fig. 6. The relation of the parts in this position is also 70 shown in elevation in Fig. 2 and in sectional elevation in Fig. 4.

It is to be noted that when the vertical rod 44 is projected vertically, the pivot 46 by which the rod is joined to its lower portion 47 is aligned 75 with the hinges 18 at the junction of the door

sections 10 and 11, thus permitting the rod 44 to break at the hinge and swing rearwardly with the upper door section 10. This is best illustrated in the sectional detail in Fig. 4.

With the parts in the positions shown in Figs. 2, 4 and 6, the door may either be locked by throwing the bolt 60 through a slot in the vertical rail 19 or by projecting a bolt through the hole 61 in the face of the rail 19, into the path of the bearing assembly mounted on section 12 of the door.

If it is desired to open the entire door after the uppermost section has been swung into the position shown in Figs. 2, 4 and 6, the bolts just described can be released and the door can be manually lifted by the handle 62 with the aid of the springs or counterweights which may be connected to the cables 23.

As the door is lifted the various bearings will ride upon the angle rail 19 about the curved portion 20 and finally upon the horizontal portion 21 of the rail affixed to the ceiling. The upper frame-piece 63 of the uppermost section 10 of the door is borne upon the arm 37 of the bracket 35 and the entire door section 10 is thus carried upon the wheels 42, 43 mounted upon the bracket 35, both about the curved track 20 and throughout the horizontal travel of the door upon the tracks 21. The entire door can thus be rolled around the curve 20 and into a horizontal position. No clearance of any kind is required above the door and the rail 21 may be mounted beneath the ceiling of the room and spaced from it by merely the thickness of the door.

Having thus described my invention, what I claim as new and desire to secure by Letters Patent of the United States is:

1. A door comprising a plurality of hinged sections, bearing means upon each of said sections except the uppermost section comprising three rollers to engage opposite faces and one edge of an angle beam, angle beams located along both edges of said door and forming tracks to guide said door from a vertical to a horizontal position at the ceiling, bearing means on the uppermost section engaging said angle beams and manually operable means to swing the uppermost section of said door into an inclined position to enable the door to be raised into a horizontal position guided by the angle beam trackways.

2. A bearing unit pivotally mounted upon the uppermost section of an overhead door comprising an arm pivoted at one end to said section, a link pivoted to the other end of said arm, a roller mounted upon the pivot of said link, a second roller mounted upon the other end of said link, and manually operable means by which said arm may be moved from a horizontal position normal to said door section into a position parallel to said door section.

3. A bearing unit pivotally mounted upon the uppermost section of an overhead door comprising an arm pivoted at one end to said section, a link pivoted to the other end of said arm, a roller mounted upon the pivot of said link, a second roller mounted upon the other end of said link, and means by which said arm may be moved from a horizontal position normal to said door section into a position parallel to said door section, said means consisting of a vertical rod by which said horizontal arm can be lifted into the latter position, a horizontal bar, and a series of links by which motion of said horizontal bar can be translated into movement of the vertical rod.

4. A bearing unit pivotally mounted upon the uppermost section of an overhead door comprising an arm pivoted at one end to said section, a link pivoted to the other end of said arm, a roller mounted upon the pivot of said link, a second roller mounted upon the other end of said link, and means by which said arm may be moved from a horizontal position normal to said door section into a position parallel to said door section, said means consisting of a vertical rod pivoted to said horizontal arm, a toggle beneath said vertical rod and pivoted thereto, means to guide said toggle from closed to an open vertical position, a horizontal bar pivoted to one link of said toggle and a lever for imparting a horizontal motion to said horizontal bar.

5. A bearing unit pivotally mounted upon the uppermost section of an overhead door comprising an arm pivoted at one end to said section, a link pivoted to the other end of said arm, a roller mounted upon the pivot of said link, a second roller mounted upon the other end of said link and means by which said arm may be moved from a horizontal position normal to said door section into a position parallel to said door section, said means consisting of a vertical rod, a toggle connected to the lower end of said rod, and means to open said toggle and impart vertical movement to said vertical rod, said last named means comprising a horizontal bar pivotally connected to the lower link of said toggle, and a lever for imparting horizontal motion to said horizontal bar.

6. Means for swinging a hinged section of an overhead door comprising a lever, a rotatable plate secured and rotated by said lever, a horizontal bar eccentrically pivoted at its inner end to said plate and having the other end extending beyond the outer edge of the door to engage a guide rail when the door is in closed position and lock the door against vertical motion, a toggle pivotally mounted upon said door and operated by said bar, a vertical rod pivoted to and operated by said toggle, a horizontal arm pivotally secured to the uppermost section of said door and pivotally connected at its outer end to said vertical rod, and a link pivotally mounted upon said horizontal arm and bearing two rollers to receive between them the guide rail.

7. A multi-section overhead door comprising a plurality of hinged door sections, bearing means upon each of said sections, a track on each side of the door with a vertical rail parallel to the door frame curved at the top of the door opening into a horizontal rail normal to the vertical rail, and means to tilt the uppermost section of the door without any vertical movement of said door, said means comprising an arm pivoted at one end to said uppermost door section, wheels mounted upon the other end of said arm and spaced apart to receive the track rail between them, and manually operable means for varying the angle between said arm and the uppermost door section.

8. A door comprising a plurality of hinged sections adapted to fit in a door frame, tracks adjacent the sides of the door frame, bearing means on the door sections engaging the tracks to guide the door sections into and out of the frame, and means forming a movable connection between one edge of the uppermost door section and its corresponding bearing means movable to vary the distance between said edge and said bearing means for swinging the uppermost section

to a partially opened position without affecting the other door sections.

9. A door comprising a plurality of hinged sections adapted to fit in a door frame, tracks adjacent the sides of the door frame, bearing means on the door sections engaging the tracks to guide the door sections into and out of the frame, means forming a movable connection between one edge of the uppermost door section and its corresponding bearing means movable to vary the distance between said edge and said bearing means for swinging the uppermost section to a partially opened position without affecting the other door sections, manual control means mounted on a door section below the uppermost section, and a jointed linkage connecting said control means to said connection means.

10. A door comprising a plurality of hinged sections adapted to fit in a door frame, tracks adjacent the sides of the door frame, bearing means on the door sections engaging the tracks to guide the door sections into and out of the frame, means forming a movable connection between one edge of the uppermost door section

and its corresponding bearing means movable to vary the distance between said edge and said bearing means for swinging the uppermost section to a partially opened position without affecting the other door sections, a latch on one of the lower door sections to latch it against sliding movement on the tracks, manual control means for the latch, and a jointed linkage connecting said control means to said connection means.

11. A door comprising a plurality of hinged sections adapted to fit in a door frame, tracks adjacent the sides of the door frame, bearing means on the door sections engaging the tracks to guide the door sections into and out of the frame, link means pivotally connected at one end to the upper edge of the top door section and at its opposite end to the corresponding bearing means, and means for changing the angle of said link means relative to said door section to move said door section to partially open position without affecting the other door sections.

FRANK O. GOODMAN.
